[57] CLAIM

The ornamental design for a potters wheel, as shown.

DESCRIPTION

FIG. 1 is a perspective view of the potters wheel showing my new design;

FIG. 2 is a front view thereof;

FIG. 3 is a side view taken from the right of FIG. 1, the side opposite being a mirror image thereof except for the absence of the foot pedal;

FIG. 4 is a top view thereof; and,

FIG. 5 is a bottom view thereof.
